METHOD OF MAKING A BUFFING WHEEL OR
WHEEL SECTION AND THE PRODUCT
THEREOF

Elisha W. Hall, Scituate, Mass.

Application September 16, 1937, Serial No. 164,196

10 Claims. (Cl. 51—193)

This invention relates to a novel and improved method of making a buffing or polishing wheel or wheel section and the product thereof. Heretofore, in the manufacture of a buffing or polishing wheel or wheel section, if a strip of buffing or polishing material such as cloth be wound about a hub to the thickness required at the periphery of the wheel, the thickness of such material is so much greater than that of the hub that difficulty is experienced in preventing the cloth from overlapping the outer margin of the hub. On the other hand, if the hub be made thicker, then it prevents obtaining the proper density of the cloth when clamping a wheel or a number of wheel sections onto an arbor.

In accordance with the present invention, these difficulties are avoided by employing a hub which is readily compressible in an axial direction and which has an initial thickness approximating what is to be the aggregate thickness of the buffing or polishing material. The latter may then be applied to the hub without danger of its overlapping the hub, anchor disks applied to the faces of the hub and buffing or polishing material, the parts being united as by adhesive, and the assembly then compressed under great pressure which reduces the thickness of the hub to that required for use, and when the pressure is removed, the hub remains permanently compressed, while the unrestrained part of the cloth, being resilient, expands to the thickness required at the periphery. Thus, the hub presents no obstacle to obtaining the pressure on the cloth, necessary to provide the proper density of the latter when clamping the wheel or wheel section on an arbor. The anchor disks may desirably be secured on the one hand to the cloth and on the other hand to the hub by stitching. Thus there is produced a wheel or wheel section having a desirably thin hub and a desirably thicker working face, so that the hub will not interfere with the proper clamping by clamping disks onto an arbor.

The invention will best be understood by reference to the following description when taken in connection with the accompanying drawings illustrating the method and the product thereof, while its scope will be pointed out more particularly in the appended claims.

In the drawings:

Fig. 1 is a side elevation of a buffing wheel or wheel section made in accordance with the invention;

Fig. 2 is an edge elevation of the same;

Fig. 3 is a side elevation of one of the collapsible disks, of which the hub is to be constituted;

Fig. 4 is an edge elevation of the same;

Fig. 5 is an elevation of a portion of the bias-cut strip of warp and woof cloth which is to constitute the buffing or polishing material;

Fig. 6 is a side elevation of the strip of cloth ruffled to reduce the length of one of its edges preparatory to assembly with the hub;

Fig. 7 is an edge elevation of the ruffled margin of the cloth strip;

Fig. 8 is a vertical, sectional view illustrating steps in the assembling and uniting of parts;

Fig. 9 is a sectional view of the complete assembly in readiness to be compressed; and

Fig. 10 is a sectional view of the assembly after the pressure has been removed.

Referring to the drawings and to the method and the product of the method illustrated therein, and having reference at first to Fig. 5, there is shown a strip 11 of appropriate cloth such as canton flannel, twill, duck, or sheeting, the material shown being bias-cut, warp and woof cloth. As shown, there is employed a single layer of cloth, although in some cases it may be desirable to employ a plurality of superposed plies.

The first step is to shorten the strip along one edge by ruffling the same for example as shown in Fig. 6, and securing the ruffles as by one or more, herein two, rows 13 and 15 of 30 stitches. This may conveniently be accomplished by the use of a two-needle sewing machine equipped with a ruffling attachment.

The next step or steps may be varied somewhat, as desired. A hub 17 may be prepared first, and then assembled with the ruffled strip and the anchor disks, but a convenient mode of assembly, and the one which it is preferred to employ is, first to take an anchor disk 19 of suitable material such as sheeting, twill, or canvas provided with a small, central hole 21, place it over a centering or pilot pin 23 upon a turn-table 25, and apply adhesive such as latex to the upper face of the disk as by a spray nozzle 27. The previously prepared hub as an entirety may now be placed on and about the centering pin and superimposed upon the tacky surface of the anchor disk, but a more convenient way, and the one which it is preferred to employ, is to build up the hub upon the pin.

A desirable hub, and the one which it is preferred to employ, is composed of a plurality of plies or sheets, herein three sheets 29, of corrugated cardboard, each with a central hole 31. Ordinary, commercially obtainable, corrugated

cardboard is desirably employed, and comprises two outer, flat sheets 33 and an intermediate, corrugated sheet 35, all of which are adhesively united. This material is readily compressible or collapsible under sufficient pressure because of its cellular characteristic.

According to the preferred mode of assembly, one of these disks is placed upon and about the centering pin and is superimposed upon the tacky, upper surface of the anchor disk. The upper surface of this corrugated cardboard disk is then coated with adhesive as by spraying it with latex, a second, corrugated cardboard disk is placed upon the tacky upper surface of the first, the upper surface of the second is sprayed with latex, and a third is then placed upon the second. The upper surface of the third disk may now be sprayed with latex but it is perhaps more desirable to do so later.

20 The hub is now complete and in readiness for the assembly therewith of the ruffed strip. A convenient mode of applying the strip, and the one which is employed in the present example is to place the free end of the strip upon the tacky, 25 exposed margin of the anchor disk and secure it as by a thin clamp, if need be, and to rotate the turntable, meanwhile coiling the strip helically about the hub with the ruffed margin of the strip toward the hub. During the coiling, 30 the successive convolutions of the strip, close to the hub, and the periphery of the hub are sprayed with latex so that the convolutions adhere to one another and to the hub. When the coiling of the strip has proceeded to a point 35 where the strip has been built up to a thickness approximating that of the hub, the strip is severed preferably at a point in line with the first end.

The upper surface of the upper, carboard disk 40 is now sprayed with latex, or alternatively a second, anchor disk 37 (see Fig. 9) provided with a central hole 39 is sprayed with latex and placed, with its tacky surface downwardly upon the top of the uppermost, corrugated cardboard disk. 45 The assembly is now complete and may be removed from the centering pin and turntable and placed in a powerful press under a pressure of several tons which compresses the assembly and collapses the hub to the final thickness which it 50 is to have. The pressure may be so great that the cells of the corrugated cardboard are utterly and completely collapsed so that they cannot be seen except upon close inspection, although, usually, it is practically impossible to distinguish 55 any cellular appearance at all. This is simply a matter of the extent to which the compression is carried.

When the assembly is removed from the press, it is found that while the hub remains compressed and collapsed to the desired thickness, the cloth strip and the margins of the anchor disks, being resilient, spring out, more especially at the periphery (see Fig. 10) to the dimension required for the working surface of the wheel or wheel section.

60 The parts are now strongly united by adhesive between the anchor disks, and the hub, and the coiled strip, and between the latter and the periphery of the hub, and between the constituent 65 layers of the hub. Furthermore, the wheel or wheel section, except at its marginal portion, possesses a desirable degree of rigidity. It is possible that, under some circumstances, without further fastening, the wheel or wheel section might possess sufficient strength for use, but I prefer to add 70

strength by sewing the margins of the anchor disks to the coiled strip by a row of through and through stitches 41, and further sewing the anchor disks to the hub by a row of through and through stitches 43 (see Fig. 1).

5 All that now remains is to punch a central hole of the required shape and dimensions and to trim the margin of the wheel or wheel section true. In the present example, a large, square hole 45 is punched and the wheel or wheel section is 10 placed upon a square arbor, after which the periphery is suitably trimmed smooth and concentric with the axis of the arbor. The wheel or wheel section is now complete and ready for use either alone or in combination with one or more 15 like sections upon the arbor of an appropriate machine.

Having thus described the method of making a wheel or wheel section and the product thereof, what I claim, and desire by Letters Patent 20 to secure is:

1. The method of making a buffing or polishing wheel or section, which comprises assembling about a readily compressible hub, buffing or polishing material having a thickness approximating the thickness of said hub, and assembling with said hub and with said material two anchoring disks, one on each face of said hub and overlapping said material, compressing the entire mass axially, thus permanently reducing 30 the axial thickness of the hub, and then releasing the pressure and allowing the buffing or polishing material to expand to an axial thickness greater than that of the hub.

2. The method of making a buffing or polishing wheel or wheel section, which comprises assembling and adhesively securing together the following elements, namely a readily compressible hub, buffing or polishing material about said hub, and two anchoring disks, one on each face 40 of said hub and overlapping said material, compressing the mass axially, thus permanently reducing the axial dimension of the hub, and then removing the pressure and allowing the buffing or polishing material to expand to an axial dimension greater than that of the hub.

3. The method of making a buffing or polishing wheel or wheel section, which comprises helically winding a strip of buffing or polishing material about a readily compressible hub, adhesively uniting said material with said hub, adhesively uniting two anchor disks with opposite faces of said hub, compressing the mass axially, thus permanently reducing the axial dimension of the hub, and then removing the pressure and allowing the buffing or polishing material to expand to an axial dimension greater than that of the hub.

4. The method of making a buffing or polishing wheel or wheel section, which comprises 60 ruffling a strip of buffing or polishing material along one edge, winding the strip about a readily compressible hub with the ruffled edge adjacent the hub, adhesively uniting the ruffled edge with the hub, adhesively uniting two anchor 65 disks with opposite faces of the hub, compressing the mass axially, thus permanently reducing the axial dimension of the hub, and then removing the pressure and allowing the buffing or polishing material to expand to an axial dimension 70 greater than that of the hub.

5. The method of making a buffing or polishing wheel or wheel section, which comprises ruffling a strip of buffing or polishing material along one edge, helically coiling the strip about 75

- 5 a readily compressible hub with the ruffled edge adjacent the hub, adhesively uniting the ruffled edge with the hub, adhesively uniting two anchor disks with opposite faces of the hub, compressing the mass axially, thus permanently reducing the axial dimension of the hub, and then removing the pressure and allowing the buffing or polishing material to expand to an axial dimension greater than that of the hub.
- 10 6. In a buffing or polishing wheel or wheel section, the combination of an axially collapsed, cellular hub, a body of buffing or polishing material about and adhesively united with said hub, and two anchor disks adhesively united with said hub and overlying and united with said buffing or polishing material.
- 15 7. In a buffing or polishing wheel or wheel section, the combination of a hub comprising a plurality of thicknesses axially collapsed, corrugated cardboard, a body of buffing or polish-
- 20

ing material about and adhesively united with said hub, and two anchor disks adhesively united with said hub and overlying and united with said buffing or polishing material.

8. A buffing or polishing wheel hub comprising a plurality of superposed, adhesively united sheets of corrugated cardboard having a common, central opening.

9. In a buffing or polishing wheel or wheel section, the combination of an axially collapsed, 10 cellular hub, and an annular body of buffing or polishing material about and secured to said hub.

10. In a buffing or polishing wheel or wheel section, the combination of an axially collapsed, cellular hub, and an annular body of buffing or 15 polishing material comprising a plurality of layers adhesively secured to one another and to said hub.
